(57) **CLAIM**

The ornamental design for a garment, as shown and described.

DESCRIPTION

FIG. 1 is a perspective view of a garment showing our design according to a first embodiment;

FIG. 2 is a side view thereof;

FIG. 3 is a front view thereof;

FIG. 4 is a rear view thereof;

FIG. 5 is a perspective view of a garment showing our design according to a second embodiment;

FIG. 6 is a side view thereof;

FIG. 7 is a front view thereof; and,

FIG. 8 is a rear view thereof.

The long-and-short broken lines form an unclaimed boundary around the claimed subject matter, and form no part of the claim. The even-length broken lines, which show the remainder of the article, are directed to environment, represent unclaimed subject matter, and form no part of the claim.

1 Claim, 8 Drawing Sheets(56)
